DISPLAY PACKAGE

Irwin Nutt, Los Angeles, Calif.

Application April 17, 1935, Serial No. 16,781

3 Claims. (Cl. 206—44)

My invention relates to a display package or carton particularly intended for use for the packaging of food products such as cookies, crackers, candy and the like or for medicinal tablets or for any product that is put up in packages or cartons for retail sale.

The principal object of my invention is, to provide a package or carton that is formed of cardboard or the like and which has one or more of its walls cut so as to provide portions that may be pressed inward a short distance to provide a pocket or recess adapted to receive one or more of the pieces of merchandise that are contained in the package in order that said pieces of merchandise may be conveniently displayed through the transparent outer wrapper of the package, thus enabling a prospective purchaser to readily note the particular form and character of the goods contained within the package or carton.

A further object of my invention is, to provide a display package or carton of the character referred to that may be readily packed and piled one on top of the other or side by side without possibility of breakage of the pieces of merchandise that are displayed on one of the walls of said package.

With the foregoing and other objects in view my invention consists in certain novel features of construction and arrangements of parts that will be hereinafter more fully described and claimed and illustrated in the accompanying drawing in which:

Fig. 1 is a perspective view of a merchandise package or carton constructed in accordance with my invention and showing the front wall thereof formed so as to display four pieces of merchandise.

Fig. 2 is an enlarged vertical cross section taken on the line 2—2 of Fig. 1.

Fig. 3 is an enlarged horizontal section taken on the line 3—3 of Fig. 1.

Fig. 4 is an enlarged elevational view of a portion of one of the carton walls and showing the manner in which the same is cut to form a de-pressible portion adapted to receive a piece of merchandise for display.

Fig. 5 is a horizontal section taken on the line 5—5 of Fig. 4.

Fig. 6 is an elevational view similar to Fig. 4 and showing the wall of the carton cut to form a rectangular de-pressible portion.

Referring by numerals to the accompanying drawing which illustrates a preferred embodiment 55 of my invention, 10 designates the body of the

carton which may be of any size and shape and preferably formed of cardboard.

Where the wall of the carton is cut for the display of substantially circular or disc-like pieces of merchandise such as cookies, crackers, candy and the like, the front wall of the container or carton is cut to form a series of arcuate slits 11 that are disposed in relative circular arrangement, such arcuate cuts being approximately ninety degrees in length and the ends thereof spaced apart to form short uncut portions 12.

From one end of each slit 11, adjacent the uncut portion 12, the slit 11 is extended outward a short distance as designed by 13 and the outer end of this slotted portion joins the end of an arcuate slit 14 that is formed in the cardboard forming the wall of the carton a slight distance outwardly from and concentric with the slits 12.

The length of the outer arcuate slit 14 is such that it extends a substantial distance beyond the end portion of the adjacent concentric slit 11, thereby forming a short arcuate tongue or connecting strip 15 that connects the wall of the carton or container with the disc 16 that is formed by cutting the arcuate slits 11. Thus one end of the connecting member or tongue 15 is connected to the wall of the carton at a point intermediate the ends of the adjacent slit 11 and the opposite end of said slit 14 is connected by means of the uncut portion 12 to the edge of the disc 16.

After the wall of the carton or container has been cut as described, the disc 16 may be readily pressed inward a short distance so as to form a space or pocket between the disc and the wall of the carton with said disc connected to the wall by the tongues or connecting strips 15 and the circular space thus formed is adapted to receive a cookie, cracker or other disc-like product.

The connecting members 15 arranged around the edges of the product receiving space or pocket holding said product in proper position within the pocket and prevents said product from dropping or moving out of the pocket in any direction.

In packing cartons constructed in accordance with my invention, a retaining member 17, preferably formed of heavy paper or thin cardboard is arranged to the rear of and parallel with the wall that is cut to form the product receiving pockets and the vertical edges of this member 17 are bent forwardly at right angles as designated by 18, so as to engage directly against the inner faces of the side walls of the carton to the rear of the front wall therein (see Fig. 3).

The intermediate portion of the inserted mem-

ber 17 is bent double to form a vertically disposed forwardly extending rib 19 that extends to the front wall of the carton and as a result of this construction two vertically disposed channels are formed immediately to the rear of the front wall of the carton and which channels receive the depressed discs 16 and the product that is positioned thereupon.

The space between the spacing member 17 and the rear wall of the carton is filled with the contents of the package, which contents if desired may be packed in a moisture proof bag and after the ends of the carton have been closed the entire carton is enclosed by a transparent wrapper such as cellophane.

Thus the articles of merchandise positioned on the discs 16 are prominently displayed on the front wall of the package and said goods as well as all printed matter on the container or carton are readily visible through the transparent wrapper.

In Fig. 6 I have illustrated the front wall of a carton slotted to form a substantially square compressible portion 20 adapted to receive square articles of merchandise to be displayed and the sides of this compressible portion are connected by short parallel tongues or connecting strips 21 to the wall of the carton from which the member 20 is cut.

Thus it will be seen that I have provided a display package or carton that is relatively simple in construction, inexpensive of manufacture and very effective in performing the functions for which it is intended.

The articles of merchandise positioned on the depressed portions of the carton wall and covered by the outer wrapper of transparent material are conveniently and attractively displayed and by

reason of their position beneath the outer face of the front wall of the carton, the displayed articles of merchandise are protected against breakage even when the cartons are piled one on top of the other or side by side for transportation. 5

It will be understood that minor changes in the size, form and construction of the various parts of my improved display package may be made and substituted for those herein shown and described without departing from the spirit of my 10 invention, the scope of which is set forth in the appended claims.

I claim as my invention:

1. In a display package, a wall cut through to form a plurality of slits with the end portion of 15 each slit offset from and extending past the adjacent end of the next slit to form connecting members between the wall of the package and that portion enclosed by said slits.

2. In a display package, a wall provided with 20 a series of slits with one end of each slit offset from and extending past the adjacent end of the next slit and the material between the overlapping ends of the slits constituting an unbroken connection between the wall of the package and 25 that portion surrounded by said slits.

3. In a display package, a wall provided with a series of slits with one end of each slit offset from and extending past the adjacent end of the next slit and the material between the overlapping ends of the slits constituting an unbroken connection between the wall of the package and that portion surrounded by said slits and which unbroken connection lies parallel with the adjacent edge of that portion of the wall that is 30 surrounded by the slits.

IRWIN NUTT.
